Primary Examiner — Justin C Dodson*Assistant Examiner* — Matthew Bird(74) *Attorney, Agent, or Firm* — Synergy Patent Group(57) **CLAIM**

The ornamental design for a water filter as shown and described.

DESCRIPTION

FIG. 1 is a top perspective view of one embodiment of a water filter;

FIG. 2 is a side elevation view thereof;

FIG. 3 is a top plan view thereof;

FIG. 4 is a bottom plan view thereof; and,

FIG. 5 is another perspective view thereof, shown in an environment of use.

The broken line showing the water filter is for the purpose of illustrating portions of the article and forms no part of the claimed design.

1 Claim, 5 Drawing Sheets(56)
